UNITED STATES PATENT OFFICE.

JAMES H. McNAMARA, OF CHICAGO, ILLINOIS.

DESIGN FOR A TRUNK-FASTENER.

SPECIFICATION forming part of Design No. 23,178, dated April 10, 1894.

Application filed February 19, 1894. Serial No. 500,792. Term of patent 14 years.

To all whom it may concern:

Be it known that I, JAMES H. McNAMARA, a citizen of the United States, and a resident of Chicago, in the county of Cook and State of Illinois, have invented and produced a new and original Design for Trunk-Fasteners, of which the following is a specification, reference being had to the accompanying drawing, forming a part hereof.

10 This design relates to trunk fasteners for trunks, cases and the like, and has for its object to provide a novel and ornamental fastener which presents to the eye a distinguishing and characteristic appearance.

15 The leading feature of the design consists of the general U-shaped base, triangular-shaped crown and an oblong-shaped center-piece overlapping the joint between the crown and base, the faces of all of the parts lying 20 in the same general plane.

The design is illustrated in the accompanying drawing, in which the figure is a perspective view of a fastener embodying the design.

25 In the drawing A indicates the U-shaped base, B the triangular crown and C the general oblong rectangular center-piece overlapping the horizontal joint between the upper edge of the base and the lower edge of the 30 crown. The base consists generally of a flat

rectangular lower end from which project at each end thereof the vertical side arms *b* which terminate at their upper ends in the horizontal, lateral projections *c*, the whole base having the general outlines of the letter **U**. 35

The center-piece *C* is of an oblong rectangular flat form, the body portion of which fits between and lies substantially flush with the side arms *b* of the base but is provided with an extension *d* at its upper end, also of oblong rectangular shape, which lies in an inverted U-shaped recess *e* formed in the face of the lower central portion of the crown *B*.

The crown is of general triangular form 45 having a straight, horizontal lower edge, oblique side edges, with squared ends *f* at the lower corners thereof and a rounded end *g* at the apex thereof joining the two oblique sides.

The design provides a fastening for trunks, 50 cases and other like receptacles, which presents to the eye an ornamental, distinguishing and characteristic appearance.

What I claim is—

The design for a trunk fastening as shown 55 and described.

JAMES H. McNAMARA.
